UNITED STATES PATENT OFFICE

141,453

DESIGN FOR A PULL TOY

Leo Wolf, Chicago, Ill.

Application February 23, 1945, Serial No. 118,107

Term of patent 3½ years

(Cl. D34—15)

To all whom it may concern:

Be it known that I, Leo Wolf, a citizen of the United States and a resident of Chicago, in the county of Cook and State of Illinois, have invented a new, original, and ornamental Design for a Pull Toy, of which the following is a specification, reference being had to the accompanying drawing forming a part thereof, and in which:

Fig. 1 is a perspective view of a pull toy showing my new design.

Fig. 2 is a top plan view, a portion of the pull-cord being broken away for convenience in illustration; and

Fig. 3 is a front elevational view of Fig. 2.

I claim:

The ornamental design for a pull toy, as shown.

LEO WOLF.
